FIG. 3

Des. 195,085

PAGE 4

FIG. 4

FIG. 5

FIGURE 1 is a front elevational view of a disc file, showing my new design;

FIGURE 2 is a rear elevational view thereof;

FIGURE 3 is a top plan view thereof;

FIGURE 4 is a right side elevational view thereof; and

FIGURE 5 is a left side elevational view thereof.

I claim:

The ornamental design for a disc file, as shown.
